UNITED STATES PATENT OFFICE.

MARTIN HOFFMAN, OF DETROIT, MICHIGAN.

METHOD OF FORMING CEMENTITIOUS BLOCKS.

Application filed July 30, 1927. Serial No. 209,538.

This invention relates to methods of forming cementitious blocks and particularly to methods for imparting an ornamental appearance to such blocks during formation thereof.

- An object is to so utilize differently colored cementitious mixtures in forming a building block or the like as to secure an ornamental mottled effect.
- 10 A further object is to obtain such an effect in a sufficiently simple manner to avoid any considerably increased cost as compared to the production of plain blocks.

These and various other objects the invention attains by the construction hereinafter described and illustrated in the accompanying drawing, wherein:

- 20 Figure 1 is a front elevation of a mantel made of my improved blocks and illustrating one ornamental surface effect which may be secured by the herein disclosed method.

Figure 2 is a perspective view of one of the blocks.

- 25 Figure 3 is a detail sectional elevation of the block shown in Figure 2, and

Figure 4 is a similar section through a block having two faces mottled in accordance with my improved method.

- 30 In practicing said method there is employed a mold formed of wood or any other suitable material and having any desired shape according to the contour of the block to be formed. Two or more cementitious mixtures are employed differing in any desired manner as to color, but preferably otherwise comprising the same ingredients.

35 The operator first scatters upon the bottom of the mold a quantity of one of said mixtures insufficient to cover said bottom and then similarly scatters upon the mold bottom a quantity of another mixture, differing in color. This alternate delivery of the two mixtures into the bottom portion of the mold is repeated until there is formed a surfacing

40 layer A of material preferably varying from one-quarter to one-half inch in thickness. The mold is now filled up with cementitious material B regardless of color and preferably of cheaper ingredients, and its contents are then tamped to compact them to a suitable degree. If three or more mixtures are to be employed they are introduced

separately and intimately mixed in the mold, repetition of the cycles of introduction being continued until the desired depth of the facing is reached.

Preferably the mixtures thus employed are relatively dry carrying only sufficient moisture to assure a proper cohesion of the particles when the mold is tamped. After 60 tamping, the block may be removed from the mold and allowed to cure while moisture is maintained thereon, as by intermittent spraying.

By mixing materials in the described 65 manner there is imparted to that surface of the block which seats upon the bottom of the mold a very pleasing ornamental effect rendering the block particularly desirable for fire-place construction or any other interior use.

Should it be desired to present my improved mottled ornamentation on two or more faces of the block, each face may be covered separately as above described and 75 then held against the mold by a temporary partition wall while the mold is turned to bring another face to the bottom of the mold for receiving the mottling mixtures. The backing material may then be applied either 80 before or after the temporary partitions are removed.

In Figure 4 I have shown in cross-section a block made in this manner with two faces A¹ and A² formed by my improved mottling 85 process and the backing material C reinforcing both mottled faces.

What I claim is:

The method of forming a mottled ornamental cementitious block, consisting of 90 scattering promiscuously upon the bottom of a mold a colored mixture of cementitious material so as to partially cover said bottom, then promiscuously scattering upon said bottom a quantity of a differently colored mixture and repeating these alternate steps until the bottom portion of the mold is fully covered to a suitable depth, and finally filling the mold with cementitious material regardless of color.

In testimony whereof I hereunto set my hand.

MARTIN HOFFMAN.
